UNITED STATES PATENT OFFICE.

CARRIE BROWNELL AVERILL, OF FORT WAYNE, INDIANA.

BABY-CARRIER.

1,039,009.

Specification of Letters Patent. Patented Sept. 17, 1912.

Application filed November 11, 1911. Serial No. 659,734.

To all whom it may concern:

Be it known that I, CARRIE BROWNELL AVERILL, a citizen of the United States, residing at Fort Wayne, in the county of Allen and State of Indiana, have invented new and useful Improvements in Baby-Carriers, of which the following is a specification.

This invention relates to certain novel and useful improvements in a device adapted to be worn for the purpose of supporting and carrying infants or small children.

In carrying out my invention, it is my purpose to provide a carrier, which is in the nature of a sling or flexible receptacle which is adapted to be strapped about the shoulders and waist of a person in such manner that the infant may be carried therein safely, securely and conveniently, and without undue fatigue, and, furthermore, when my device is in use, the hands of the person carrying the infant are not encumbered, but such person has the use of both hands for other purposes.

Still a further object of my invention is to provide a device of the class described which may be constructed of canvas, leather or any other suitable material, and which will embody the desired features of simplicity and durability, and which may be manufactured and marketed at a relatively low cost.

With the above-recited objects, and others of a similar nature, the invention consists in the construction, combination and arrangement of parts set forth in and falling within the scope of the appended claim.

In the drawing:—Figure 1 is a detail perspective view of the carrier embodying my invention. Fig. 2 is a view, showing the application of the same.

Referring now to the accompanying drawings in detail, the numeral 1 indicates the sling or receptacle portion of the device, which in the present instance is in the nature of a flexible bag which may be constructed of canvas or other suitable fabric, or of leather or other material. This receptacle is preferably constructed of such shape that it has an approximately semicircular front edge or binding, indicated at 2, which may be provided with reinforced bands 3, and a top edge 4 which is similarly reinforced by the band 5. To the central front portion of the front edge 2, I attach

as at 6 a strap 7, bifurcated to form the two members 8—8 which are designed to diverge and are to be strapped or connected to the top edge 4 by means of the buckles 9—9 carried by the tabs 10—10 sewed to the top band or edge and suitably spaced apart. In use, this diverging strap is employed for fastening the infant in the carrier, the strap members 8—8 passing over the limbs of the infant and holding the latter securely and safely in place.

It is my intention that the carrier be supported from a person in such manner that there will be no undue strain upon the body. To support the carrier, I provide a shoulder strap 13, fastened at one end, as at 16, to the front edge, or may, if desired, be in the form of a continuation of the front edge, or binding indicated at 2, said strap 13 being adapted to pass over the shoulder and to be adjustably fastened by means of the buckle 15.

I provide a waist band 11 to keep the child in erect position, fastened at one end as at 12, to the front edge, said strap 11 being adapted to pass over the breast of the infant and encircle the waist of the person carrying the child, and to be adjustably fastened by means of the buckle 12', as shown in Fig. 1 of the drawings.

It will be seen that I have provided an exceedingly simple, yet efficient carrier by means of which the child is supported in a natural and comfortable position and is kept from falling or slipping from the carrier by means of the divided strap passing between the limbs and buckling to the back of the seat on each side, while it is kept erect by the waist strap passing across the breast and around the waist of the person carrying the child. It will further be seen that the child may be carried while the person is walking or sitting, without readjusting, and at the same time both the hands and the arms are free for other employment.

I claim:—

A baby carriage adapted to be suspended from the shoulders and comprising a flexible receptacle of approximately semicircular shape having open front and top sides, a strap connected to the lower edge of said front side, said strap being bifurcated, the bifurcations being adapted to embrace the limbs of the child within such carriage and extending upwardly toward the top edge of

the top side, means for connecting the free ends of the bifurcated portions of said strap to the top edge, a shoulder strap rigidly connected to one side of said front edge and detachably connected to the opposite side of said front edge whereby the carriage may be supported from the shoulders, and a waist band secured to said front edge and adapted to encircle the waist of the child within the

carriage and the waist of the person carrying such carriage.

In testimony whereof I affix my signature in presence of two witnesses.

CARRIE BROWNELL AVERILL.
